UNITED STATES PATENT OFFICE

152,643

DESIGN FOR A LADY'S STOCKING

William Nebel, Charlotte, N. C.

Application December 24, 1947, Serial No. 143,332

Term of patent 14 years

(Cl. D47—7)

To all whom it may concern:

Be it known that I, William Nebel, a citizen of the United States, residing at Charlotte, in the county of Mecklenburg and State of North Carolina, have invented a new, original, and ornamental Design for a Lady's Stocking, of which the following is a specification, reference being had to the accompanying drawings, forming a part thereof.

Figure 3 is a side elevation of the complete lady's stocking, showing my new design, the conventional leg and top of the lady's stocking being shown in dotted lines.

I claim:

The ornamental design for a lady's stocking, substantially as shown and described.

WILLIAM NEBEL.
